UNITED STATES PATENT OFFICE

LOUIS F. BLUME, OF PITTSFIELD, MASSACHUSETTS, ASSIGNOR TO GENERAL ELECTRIC COMPANY, A CORPORATION OF NEW YORK.

TRANSFORMER

Application filed November 28, 1928. Serial No. 322,415.

My invention relates to transformers and more particularly to transformers provided with auxiliary windings for supplying current to operate voltage and current responsive devices such as voltmeters, ammeters and relays. The voltage at which the main windings of many transformers operate is so high that if any auxiliary windings for controlling, indicating or other instruments are located near these main windings, a great deal of insulation is necessary and this is always costly and sometimes it is not easy to find space for the auxiliary windings and all the necessary insulation. The general object of the present invention is to provide a transformer with an improved arrangement of windings for controlling an indicating or other instrument, these windings being magnetically associated with the main windings of the transformer but well separated from them so that very little insulation is necessary.

The invention will be better understood from the following description taken in connection with the accompanying drawing in which Fig. 1 shows the invention as applied in connection with a shell type transformer having concentric cylindrical windings; Fig. 2 shows the invention applied in connection with a shell type transformer having interleaved windings; Fig. 3 shows the invention applied in connection with a core type transformer; Fig. 4 shows a transformer similar to that shown in Fig. 3 with the invention applied in a different manner; Fig. 5 indicates the windings shown in Fig. 1 with the paths of magnetic flux produced by the main transformer currents; and Fig. 6 is an explanatory vector diagram of magnetic fluxes.

Like reference characters indicate similar parts in the different figures of the drawing.

The transformer shown in Fig. 1 is of the shell type having a magnetic core with a central winding leg 10 and two outer legs 11 and 12 joined at their ends by yokes. The winding leg 10 is surrounded by concentric cylindrical windings 13 and 14. The currents in the main windings 13 and 14 induce magnetic flux which takes several paths as indicated in Fig. 5 where the paths at one side of the core only are shown, there being a similar dispo-

tion of flux of course at the other side of the core if the two sides of the transformer are symmetrical as is usually the case.

The invention may be best understood by considering that there are two magnetic fluxes. The magnetizing current induces a main flux Φ_M which is indicated by a broken line in Fig. 5. This flux Φ_M flows entirely in the magnetic core and links both of the main windings 13 and 14. The two load currents in the windings 13 and 14 induce the other magnetic flux Φ_L which is indicated by full lines in Fig. 5. This flux Φ_L , usually called the leakage flux, flows through the space between the windings 13 and 14 and returns in what may be considered as four separate parts Φ_A , Φ_T , Φ_B and Φ_S . As indicated in Fig. 5, the flux Φ_A links the winding 13 and flows entirely in the core, the flux Φ_T links the winding 13 and flows through the space between this winding and the winding leg 10 of the core, the flux Φ_B links the winding 14 and flows entirely in the core, and the flux Φ_S links the winding 14 and flows outside of the core. The phase relations of these fluxes will not be the same for all load conditions but are determined by the power factor of the load. They may be represented by a vector diagram such as is shown in Fig. 6.

An important characteristic of the leakage flux or of any part of it is that its value is substantially proportional to the load on the transformer. Any of the leakage fluxes which have been mentioned can therefore be used as a measure of this load. This result is attained by auxiliary windings connected to a suitable instrument such as an ammeter.

In the arrangement shown in Fig. 1, an auxiliary winding 15 surrounds the winding leg 10 of the core and an auxiliary winding 16 surrounds each of the outer legs 11 and 12 of the core. These auxiliary windings need to have only a few turns each so that the voltages induced in them are low and they are also close to the core so that they are easily insulated from the main windings 13 and 14. There is also no danger from high voltages in the circuit or in the instrument to which these auxiliary windings are connected. The auxiliary windings 15 and 16 are con-

nected in series to supply current to a suitable instrument 17 such as an ammeter.

It is clear from Fig. 5 that the auxiliary winding 15 surrounds the main flux Φ_M and the return leakage flux Φ_A . Each part of the winding 16 surrounds one half of the main flux Φ_M and one of the return leakage fluxes Φ_B . The windings 15 and 16 are so connected and the numbers of turns in them are so proportioned that the voltage in the winding 15 due to the main flux Φ_M is equal and opposite to the voltage in the winding 16 due to the main flux Φ_M . The voltage at the instrument 17 due to the main flux Φ_M is therefore zero. The total flux Φ_{15} in the winding 13 is the vector sum of the fluxes Φ_{15} and Φ_T . The total flux Φ_{14} in the winding 14 is the vector sum of the fluxes Φ_{16} and Φ_S . The voltages in the windings 15 and 16 due to the return leakage fluxes Φ_A and Φ_B will be added together, however, as will be clear from a consideration of the relative directions of the main and leakage fluxes shown by the arrows in Fig. 5. The instrument 17 will therefore be responsive to a voltage which is proportional to the leakage flux and therefore to the load on the transformer.

The transformer shown in Fig. 2 is of the shell type with interleaved windings 13 and 14. The auxiliary windings 15 and 16 are similar to the windings 15 and 16 of Fig. 1 and are similarly connected, the winding 16 being disposed on the upper yoke at opposite sides of the winding leg, however, instead of on the outer legs of the core. It is obvious that the main flux Φ_M will induce equal and opposite voltages in the auxiliary windings so that the voltage at the terminals of the circuit due to this main flux will be zero. It is also clear that the currents in the two main windings 13 and 14 will induce a leakage flux in the spaces between these windings and which will link the auxiliary winding 15 but not the auxiliary winding 16. This leakage flux will therefore induce in the auxiliary windings 15 and 16 voltages which are not equal and opposite so that a voltage due to the leakage flux and therefore proportional to the load on the transformer will be available to operate an instrument connected to the auxiliary circuit.

In both of the arrangements shown in Figs. 1 and 2, the auxiliary winding 16 is shown as disposed symmetrically at opposite sides of the core instead of being connected together as a single winding on one side of the core. The arrangements shown are considered preferable in case of possible unbalance in the two magnetic circuits through the outer legs of the core.

The transformer shown in Fig. 3 is of the core type with concentric cylindrical main windings 13 and 14. The auxiliary winding 15 surrounds one of the winding legs of the core and a single winding 16 surrounds the

upper yoke of the core. The two windings have substantially the same number of turns and each surrounds the path of the main flux Φ_M so that the voltages induced by the main flux are equal and opposite. It is obvious that the leakage fluxes linking the two windings 15 and 16 will not be equal and opposite, however, and again there will be a voltage induced by the leakage flux in the auxiliary circuit for operating an instrument and this voltage will be proportional to the load on the transformer.

In accordance with a modification of the invention, the auxiliary windings 15 and 16 may be arranged and connected to give a voltage which is proportional to the voltage of either of the main transformer windings 13 and 14. It will be apparent that an instrument such as a voltmeter, properly adjusted or calibrated, may be connected to the auxiliary windings instead of to one or the other of the main windings with much less difficulty with insulation. Fig. 4 shows this modification of the arrangement shown in Fig. 3 and it will be apparent that similar modifications of the arrangements of Figs. 1 and 2 may be made.

In the modified form of the invention, the auxiliary windings are connected in series and arranged so that their voltages are opposed. To obtain a voltage proportional to that of either of the main windings, however, the relative numbers of turns in the auxiliary windings is different from that which has been described to give a voltage proportional to the transformer load. The main and leakage fluxes shown in Fig. 5 may be represented by a vector diagram such as is shown in Fig. 6. In addition to the vectors representing the main and leakage fluxes, Fig. 6 also includes a line SR which is parallel to the vector Φ_{15} and which meets the vector Φ_{15} extended at R. It also includes a line UT which is parallel to the vector Φ_{16} and which meets the vector Φ_{16} extended at T.

To obtain a voltage proportional to that of the main winding 13, the numbers of turns N_{15} and N_{16} in the auxiliary windings 15 and 16 respectively are proportioned so that the ratio of $\Phi_{15}N_{15}$ to $\Phi_{16}N_{16}$ is equal to the ratio of OR to SR, the two windings 15 and 16 being also connected so that their voltages are opposed. This result is apparent from the vector diagram of Fig. 6, bearing in mind that the voltage of a winding is proportional to the product of the number of turns in the winding and the flux which links it. In like manner, a voltage proportional to that of the main winding 14 is obtained by proportioning the numbers of turns N_{15} and N_{16} in the auxiliary windings 15 and 16 so that the ratio of $\Phi_{15}N_{15}$ to $\Phi_{16}N_{16}$ is equal to the ratio of UT to OT, the windings 15 and 16 being connected with their voltages opposed.

It is usually difficult to calculate accurately

the distribution of the leakage flux of a transformer so that it may be difficult in some cases to predetermine just what should be the relation or proportion between the numbers of turns in the two auxiliary windings 15 and 16 to give the desired result. The foregoing description demonstrates that the desired result will follow with the numbers of turns correctly proportioned between the two auxiliary windings and, if desired, the correct proportion may be ascertained by trial.

5 The invention has been explained by describing and illustrating various modifications thereof and it will be apparent that 15 further changes and modifications may be made without departing from the scope of the invention as defined in the appended claims.

10 What I claim as new and desire to secure by Letters Patent of the United States, is,—

20 1. A transformer including a magnetic core having a winding leg and an outer section for return magnetic flux, main windings on said winding leg, an auxiliary winding on said winding leg, and a second auxiliary winding on said outer section of the core, the turns of said auxiliary windings being connected in series with the voltage of the turns on the winding leg opposed to the voltage of 25 the turns on the outer section of the core.

30 2. A transformer including a magnetic core having a winding leg and an outer section for return magnetic flux, main primary and secondary windings on said winding leg, 35 an auxiliary winding on said winding leg, and a second auxiliary winding on said outer section of the core, said auxiliary windings being connected in series with their voltages opposed, and the numbers of turns in said 40 two auxiliary windings being proportional to two vector components of a voltage proportional to an electrical condition in one of said main windings.

45 3. A transformer including a magnetic core having a winding leg and an outer section for return magnetic flux, main primary and secondary windings on said winding leg, an auxiliary winding on said winding leg, and a second auxiliary winding on said outer 50 section of the core, said auxiliary windings being connected in series with their voltages opposed, and the numbers of turns in said two auxiliary windings being proportional to two vector components of the voltage of one of 55 said main windings.

55 In witness whereof, I have hereunto set my hand this 26th day of November, 1928.

LOUIS F. BLUME.
